CARTON PACKER

Filed Nov. 2, 1939

UNITED STATES PATENT OFFICE

2,282,619

CARTON PACKER

Charles P. Swan, Decatur, and Frederick W. Dickson, Atlanta, Ga., assignors to The Coca-Cola Company, Wilmington, Del., a corporation of Delaware

Application November 2, 1939, Serial No. 302,516

4 Claims. (Cl. 226—2)

This invention relates to the soft drink industry, and more particularly to the bottling division thereof.

Beverages are commonly placed in glass containers and upon same being sealed, as by means of a crown cork, distributed to the trade. In recent years a considerable quantity of such products has been merchandised in cartons, the most popular style of which appears to be a device permitting ample display of the beverage which it carries. Many millions of such open type cartons are now used very year by bottlers throughout the United States and the world; and it is with the packing of such devices that this invention is primarily concerned.

In bottling plants, or other places of assembly, the bottled beverage as it comes from the filling line, is placed in cartons, by workers especially assigned to this task. In placing the usual six bottles in a carton, the worker must move rapidly if an appreciable number of carriers is to be filled during the day, and to this end, various instrumentalities have heretofore been devised to assist him in this operation.

In recent months a type of open carton having end straps and wide apertures near its top through which the bases of bottles are passed during the packing operation has been widely used. These cartons are initially fastened adjacent their carrying elements, as by being stitched, or glued, or stapled, and accordingly do not require closing at the plant, as in the case of numerous other devices in use in the industry. In the interest of economy of space in shipping, these end-strap cartons are folded so as to lie flat, they then being packed one on top of the other in such a manner that many thousands may be placed in a comparatively small space.

It is necessary, however, that these cartons be opened before filling, and it is also desirable that they be supported during the time which this operation is taking place.

An object of my invention is to provide a means to support cartons while they are being filled.

Another object is to provide in a device of the foregoing type, means to facilitate the opening of such cartons.

Another object is to provide a carton packer which is simple in its construction.

A still further object is to provide a packer which is economical to produce.

Another object is to provide a device of the instant type which is simple in its operation and efficient in its action.

These and other objects made apparent during the further progress of this specification are accomplished by means of our carton packer, a full and complete understanding of which will be facilitated by reference to the drawing herein, in which:

Fig. 1 is an enlarged view in perspective illustrating our carton packer; a carton and bottles being shown associated therewith.

Fig. 2 is an end view of the structure disclosed in Fig. 1.

Fig. 3 is a side view of the instant structure, the carton and bottles having been removed.

Fig. 4 is a top view of the device illustrated in Fig. 3.

Referring to the drawing, it will be seen that my packer comprises a holding and shaping element 10 having a flat bottom portion 11, curved sides 12, sloping roof portions 13, a guide notch 14, and a supporting and guide bar 15. At one end and adjacent bottom 11 may be formed a projecting guide surface 16, in which may be placed an aperture 17 to facilitate hanging the device up when it is not in use.

It will be noted that the distance between vertical side elements 12 is such as to enable a carton of the type in question to be readily inserted into the packer, yet at the same time prevent distortion of the sides of the carton, the measurement in question being approximately the same as the overall width of the carrier. Walls 12 may be cut away along an ascending line 12a in order that a maximum of support may be present, with a minimum of interference in connection with inserting the carton into the packer and removing it therefrom.

Roof elements 13 engage corresponding portions of the carton, and in conjunction with notch 14, into which the lower portion of the handle slides, serve to hold same firmly in position during the filling operation.

Special attention is now directed to supporting bar 15, which is preferably of rounded contour, and highly polished in order that a minimum of frictional resistance may be present. Element 15 prevents the upper portion of the carton from being twisted or distorted during filling, and at the same time represents an instrumentality affording no inconvenience insofar as interfering with the operation itself is concerned. It will likewise be noted that in opening the carton this element acts as a guide and lever means, enabling this function to be accomplished speedily and efficiently.

The working of my device is as follows: A carton such as 18 is lifted from a stack in which it is lying in folded or flat position; ends 19 and flaps 20 slightly pried apart, and the carton brought into engagement with guide element 15 in such manner as to insert same between said flaps, the carton then being passed transversely of supporting bar 15, and downward pressure exerted the while, so that by the time handle number 21 is ready to enter slot 14, the carton is in approximately operative position. Insertion into the slot completes the positioning, and the carrier is filled by placing end bottles 22 and 23 therein, followed by center bottle 24, which is pressed downwardly so as to force the other bottles apart, and in turn act as a key or locking element in holding the entire assembly in place. A similar filling operation occurs on the opposite side of the bottle carrier, after which same is grasped by its handle and withdrawn horizontally along bar 15, upon which the filled package is ready to be placed in the channels of trade. This is repeated quickly and efficiently a great many times during the working day.

Element 10 is preferably a casting, made of some light material such as aluminum. The device is provided with a solid end wall 12A, in order that further support may be present at this point during the packing operation.

From the foregoing it is apparent that we have disclosed a new and useful carton packer which facilitates the filling of certain cartons currently in use. That the device is economical, simple and efficient for its intended purposes.

While we have disclosed in some detail one form of our invention, we do not intend to limit ourselves thereby, but on the contrary contemplate that the appended claims shall be accorded an interpretation and scope fairly in keeping with our contribution to the art.

We claim:

1. In a device of the character described, a holding member having a flat bottom portion,

sloping sides adjacent to said bottom portion, inwardly extending roof segments connecting with said sides, a guide notch formed adjacent the inner ends of said roof segments, and a supporting bar disposed beneath said notch and extending in a plane parallel with said bottom portion.

2. In a device of the character described, a holding member having a flat bottom portion, 10 cut-away sides adjacent to said portion, inwardly extending roof segments connecting with said sides, a guide notch formed adjacent the inner ends of said roof segments, and a guide 15 bar disposed beneath said notch and extending in a plane substantially parallel with said bottom portion.

3. In a device of the character described, a shaping element having a flat bottom portion, fragmentary sides adjacent to said bottom portion, 20 inwardly extending roof elements connecting with said sides, a guide notch formed adjacent the inner ends of said roof elements, and a supporting bar disposed beneath said notch and extending in a plane parallel with said bottom portion, 25 said bar having a highly polished surface whereby a minimum of frictional resistance is encountered by an object coming into contact therewith.

4. In a device of the character described, a holding member having a flat bottom portion, a 30 projecting guide surface extending therefrom and in substantially the same plane therewith, cut-away side elements adjacent said bottom portion, inwardly extending roof elements connecting with said sides, a solid end section adjacent said sides and roof elements, a guide notch 35 formed opposite the termination of the upper ends of said roof elements, and a supporting guide bar disposed beneath said notch and extending 40 in a plane substantially parallel with said bottom portion.

CHARLES P. SWAN.

FREDERICK W. DICKSON.
